CLAIM

The ornamental design for an ear hook with removable light, as shown and described.

DESCRIPTION

FIG. 1 is a perspective view of the ear hook with removable light of the instant invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view illustrating the instant invention positioned around the ear of an individual.

The portions of figures illustrated in broken lines are for environmental purposes only and form no part of the claimed design.
